UNITED STATES PATENT OFFICE.

EUGENE W. VOGEL, OF OAK PARK, ILLINOIS, ASSIGNOR TO CHICAGO RAILWAY SIGNAL AND SUPPLY COMPANY, OF CARPENTERSVILLE, ILLINOIS, A CORPORATION OF ILLINOIS.

HIGHWAY SIGNALING APPARATUS.

1,238,848.

Specification of Letters Patent. Patented Sept. 4, 1917.

Application filed August 3, 1914. Serial No. 854,779.

To all whom it may concern:

Be it known that I, EUGENE W. VOGEL, a citizen of the United States, residing at Oak Park, in the county of Cook and State of Illinois, have invented certain new and useful Improvements in Highway Signaling Apparatus, of which the following is a specification.

My invention relates to an automatic signaling apparatus designed to be placed at the intersection of a highway with a railroad track to give warning of the approach of trains; or on a highway or street at the approach to a draw or lift bridge to advise the public of the opening of the bridge, or in other analogous situations. Devices of this type are commonly called highway signals and are used most frequently at the intersection of a roadway or street with a railroad track. The preferred form of apparatus embodying my invention is shown and will be described herein as located at and particularly designed for the intersection of a street or roadway with a railroad track.

The invention contemplates providing a signaling apparatus comprising a flag with the word "Danger" or other suitable legend imprinted or displayed thereon, which is carried by a flag-pole projected out laterally over the highway from its support, preferably in a normally horizontal position, although the position might be oblique, if desired, and automatically vibrated or waved up and down on the approach of a train. In addition, one or more illuminated signals are provided, electric lamps, for example, which are lighted during the period that the flag vibrates, the lamps preferably giving out a series of flashes. The apparatus is also provided, preferably, with a bell or other audible signal which is kept in operation during the signaling period. The particular bell mechanism which I have shown for producing the audible signal to accompany the waving of the flag is claimed herein only in combination with the other features of the apparatus; the bell mechanism, *per se*, being described and claimed in my application Serial No. 839,463, "Signal bell for railroad service," filed May 18, 1914.

The invention contemplates, further, providing the apparatus with an electric motor for driving all of the moving parts. The invention contemplates, additionally, the provision of a spring or other suitable counter-balancing device for the inner end of the flag-pole whereby this end of the pole may be made short without putting too much of a load on the motor. As an alternative construction I provide two flags operated by the same motor and arranged so that one counter-balances the other.

The invention provides, furthermore, an arrangement by which the cam mechanism for vibrating or waving the flag cannot back up the motor when the current is cut off.

The object of the invention is to provide a highway signaling apparatus having the improved features above adverted to and consisting of the new and improved constructions, arrangements and devices to be hereinafter described and claimed.

The invention is illustrated in a preferred embodiment in the accompanying drawings, wherein—

Figure 1 is an elevation of the apparatus viewed as one would see it from the highway in approaching the railroad track;

Fig. 2, a detail sectional view taken on line 2—2 of Fig. 1;

Fig. 3, a vertical sectional view of the apparatus showing the flag-pole as broken off a little beyond its fulcrum point;

Fig. 4, a sectional view taken at right angles to Fig. 3 looking toward the flag;

Fig. 5, a fragmentary section on line 5—5 of Fig. 4;

Fig. 6, a similar view on line 6—6 of Fig. 5;

Fig. 7, a detail view, in perspective, of the fixed contact forming part of the mechanism for interrupting the lamp circuit shown particularly in Figs. 5 and 6;

Fig. 8, a perspective view of the bracket casting on which the motor and the trains driven thereby are mounted;

Fig. 9, a longitudinal sectional view of the spring device for counter-balancing the short end of the flag pole;

Fig. 10, a diagrammatic view to illustrate

the general function and operation of the apparatus when located at the intersection of a highway with a railroad track; and

Fig. 11, a fragmentary sectional elevation 5 illustrating the modification above referred to, in which there are two flags in counterpoised relation.

Like characters of reference designate like parts in the several figures of the drawings.

10 By referring to Fig. 10 the relationship and operation of the principal elements of the invention as applied to a highway signal will be readily understood. A designates a flag which is waved or vibrated in a vertical plane by a cam B rotated through a reducing train of gears by a motor C. D is a bell having a rocking clapper E which is brought against the bell by a weight F that is intermittently raised and released 15 by a snail cam G driven from motor C. H designates an electric lamp carried by the flag A, and J a stationary lamp. Either one or both of these may be employed. The lamps are on a circuit K which is a shunt 20 from the motor circuit L. Current is supplied from the generator M. N is a cam wheel driven from the motor C which makes and breaks the light circuit by effecting a separation of contact O and P. As the lamps 25 will ordinarily be lighted only at night, the lamp circuit is provided with a switch Q.

The motor, and when desired, the lamps, are supplied with current automatically on the approach of a train by any suitable apparatus employed for the operation of automatic railroad signals. I have shown for this purpose a track circuit system. The track R is divided by insulation into two blocks r, r', the insulation between the two 30 blocks being substantially at the highway S. T, T', designate the track batteries and U an interlocking relay of conventional type. On the approach of a train from the left, the left-hand magnet of the relay drops its 35 armature closing the circuit through the generator and motor. When the train passes over upon the block r' the left-hand magnet picks up its armature and breaks the circuit, stopping the operation of the signaling apparatus. The armature of the right-hand magnet is held up when a train passes from 40 west to east on the block r', as is well understood by those familiar with this type of apparatus. The operation of the interlocking 45 relay is reversed but with the same effect when a train approaches a highway from east to west.

I will now describe the mechanical construction of the signaling apparatus of my 50 invention.

The flag and the mechanism for waving it.

25 designates a casing having a socket 26 for mounting it on a pole 27. The danger flag A is supported on a tubular stand or

flag-pole 28 formed with gudgeons 29 mounted in bearings 30 in a housing 31 formed on the outside of the casing 25. The inner end of the flag-pole carries an anti-friction roller 32 which bears against the cam 70 B which is fixed to a shaft 33 turning in bearings formed in a bracket member 34 (Fig. 8) secured to one side wall of the casing 25. The bracket member has a platform 35 supporting the motor C. The shaft 33 75 has fixed thereon a gear wheel 36 driven from a pinion 37 on the armature shaft of motor C through a train of reducing gears 38, 39, 40, 41.

In order to lighten the load on the motor 80 which would otherwise be considerable, in view of the fact that the inner end of the flag-pole 28 against which the cam B operates is much shorter than the outer end, the leverage of which is further increased by 85 the weight of flag A, I provide a counterbalance for the short end of the pole constructed, preferably, as follows: A coiled spring 42 surrounds and is anchored at one extremity 43 to a shaft 44 mounted in bearing blocks 45 on the side wall of the casing 25. The other end of the spring is attached at 46 to one of the bearing blocks 45. The shaft 44 has a squared end 47 for a disk 48 having a grooved perimeter formed with a 90 series of circumferentially arranged perforations 49. The short end of the pole 28 is secured to the disk 48 by a link 50 and pin 51, the latter being passed through one pair of perforations 49 after the spring 42 95 has been put under torsional strain by the application of a wrench to the squared end 47 of shaft 44. The adjustment of the link 50 on the disk 48 will, of course, depend upon the weight of the outer end of the flag 100 which the spring 42 is intended to counterpoise.

In order to prevent the weight of the flag and the cam B from backing up motor C if the mechanism were stopped with the parts 110 in a position making this possible, I provide the shaft 33 with a ratchet wheel 52 against which bears a dog 53 pivoted between lugs 54 on the bracket member 34.

Instead of having a single flag counterpoised as above described, it will be possible to provide two flags, A', A', as shown in Fig. 11, projecting from opposite sides of the casing 25 and driven by a pair of oppositely arranged cams B', B' affixed to the 115 same shaft 33' and driven by the motor as above described. With an arrangement such as this one flag will be up while the other is down, so that one counter-balances the other.

The bell.

125

The bell D is supported on a standard 55 on the top of casing 25, the clapper E, which is in the form of a bell crank, being pivoted at 56 on the standard 55. The clapper is 130

connected by a pivoted link 57 with an operating rod 58 to which is secured a weight 59. The lower end of the rod 58 carries an anti-friction roller 60 which bears upon the snail 5 cam G. The latter is on the same shaft 61 with a gear wheel 62 meshing with a gear wheel 39. An elastic pad 63 is arranged on the top of casing 25 to receive the weight 59. The cam G, revolved by motor C, raises 10 the weight and then releases the same. The weight throws the clapper against the bell.

The light signals.

15 The casing 25 is preferably formed with light openings, for example, one in each side, which are provided with lenses 63. The electric lamp J is arranged within the casing so as to project beams of light through the lenses 63 (which may be suitably colored, if desired), during the signaling period.

I also preferably provide the flag itself with one or more lights, for example, with the electric lamp H which, as shown in Figs. 25 1 and 2, is arranged at the outer end of the flag-pole 28 in a spherical casing 64 which is provided with lenses 65. The wires of the light circuit K extend through the tubular portion of the flag-pole into the casing 25.

30 Preferably the light signals are of the flashing type. To this end an interrupter is provided for the light circuit which is operated from motor C. Keyed to shaft 33 is a metal disk 66 to which is secured, by screws 67, the fiber cam wheel N having on its perimeter the steel cams 68 which operate against a roller 69 (Figs. 5 and 6) attached to a spring member 70 anchored at one end 71 to the bracket member 34 and carrying 40 at its opposite end a carbon contact block 72 which is brought against a carbon block 73 secured to a terminal plate 74 having a binding post 75 for the light circuit wire, said terminal plate being fastened to an insulating block 76 which is mounted on a lug 77 forming a part of the bracket member 34. The contacts 72, 73, are brought together each time one of the cams 68 engages the roller 69.

50 While I have described my invention as embodied in a certain preferred form of apparatus, the particular embodiment of the invention is not essential. Modifications might be made in the form, arrangement and construction of the apparatus without departure from the principles of the invention. Therefore I do not wish to be understood as limiting the invention to such particular arrangements, constructions and devices except so far as limited by the express language of the appended claims.

I claim:

1. In a highway signaling apparatus, the combination with a support, of a danger flag which projects laterally from said sup-

port, means for vibrating said flag, an electric signal lamp, and means for causing the same to be illuminated in flashes during the period of each vibration of the flag.

2. In a highway signaling apparatus, the combination with a support, of a danger flag which projects laterally from said support, a bell, a motor, and cam mechanism driven thereby at different speeds for vibrating said flag and ringing said bell. 75

3. In a highway signaling apparatus, the combination with a danger flag disposed in a substantially horizontal position, a bell and an electric signal lamp, of a motor, and mechanism driven by said motor for imparting a series of vibrating movements to the flag, sounding the bell and making and breaking the lamp circuit a plurality of times during each cycle of operation of the flag. 80

4. In a highway signaling apparatus, the combination with a danger flag disposed in a substantially horizontal position, a bell and an electric signal lamp carried by said flag, of a motor, and mechanism driven by said motor for imparting a series of vibrating movements to the flag, sounding the bell and making and breaking the lamp circuit a plurality of times during each cycle of operation of the flag. 85

5. In a highway signaling apparatus, the combination with a casing, of a danger flag fulcrumed on said casing, a motor in said casing, a cam to vibrate said flag, a reducing train between said motor and said cam, 90 a bell, and a cam driven by said motor at a different speed from said first mentioned cam for operating the bell. 95

6. In a highway signaling apparatus, the combination with a casing formed with a light opening, of a signal lamp in said casing, a danger flag fulcrumed on said casing, mechanism for imparting a succession of vibratory movements to the flag, and mechanism for automatically lighting said signal lamp in a series of flashes when the danger flag is vibrated. 105

7. In a highway signaling apparatus, the combination with a casing formed with a light opening, of a signal lamp in said casing, a danger flag fulcrumed on said casing, mechanism for imparting a succession of vibratory movements to the flag, and mechanism for automatically lighting said signal lamp intermittently when the danger flag is vibrated. 110

8. In a highway signaling apparatus, the combination with a casing, of a danger flag fulcrumed on said casing so as to project substantially horizontal therefrom, a cam to vibrate said flag, a motor for driving said cam, a bell, a cam driven by said motor for sounding the bell, a signal lamp, and interrupting mechanism driven by said motor for making and breaking the lamp circuit a 125

- plurality of times during each cycle of operation of the flag.
9. In a highway signaling apparatus, the combination with a casing, of a danger flag fulcrumed on said casing, a cam to impart a series of vibrating movements to said flag, a motor for driving said cam, a bell, a cam driven by said motor for sounding the bell, a signal lamp carried by said flag, and interrupting mechanism driven by said motor for making and breaking the lamp circuit so as to emit a series of flashes during each cycle of operation of the flag.
10. In a highway signaling apparatus, the combination with a support, of a danger flag fulcrumed near its inner end on said support, mechanism for vibrating the flag, a counterbalancing spring engaged with the short end of said flag to lessen the load on the vibrating mechanism, and means for varying the tension of said spring.
11. In a highway signaling apparatus, the combination with a support, of a danger flag fulcrumed near its inner end on said support, mechanism for vibrating said flag, a torsion spring engaging the short end of the flag to lessen the load on the vibrating mechanism, and means for varying the tension of said spring.
12. In a highway signaling apparatus, the combination with a support, of a danger flag fulcrumed near its inner end on said support, mechanism for vibrating the flag comprising a cam which bears against the short end of said flag, and counterbalancing means engaged with said flag at said end to lessen the load on the cam.
13. In a highway signaling apparatus, the combination with a support, of a danger flag fulcrumed near its inner end on said support, mechanism for vibrating the flag, a revolute disk, a helical spring anchored at one end to a stationary part of the apparatus, means for securing the other end of said spring to said disk, and a link connecting the short end of said flag with said disk.
14. In a highway signaling apparatus, the combination with a support, of a danger flag fulcrumed near its inner end on said support, a cam bearing against the short end of the flag, mechanism for driving said cam, a revolubly mounted disk, a helical spring anchored at one end to a stationary part of the apparatus, means for attaching the other end of said spring to said disk, and a link connecting the short end of said flag with said disk.
15. In a highway signaling apparatus, the combination with a support, of a flag fulcrumed on said support, a cam for vibrating the flag, an electric motor for driving the cam, and locking means for preventing the aforesaid mechanism from backing up the motor when the current is cut off.
16. In a highway signaling apparatus, the combination with an upright support, of an arm fulcrumed near its inner end on said support and adapted to normally project at right angles thereto, a light signal on said arm, mechanism for imparting a succession of vibratory movements to said arm, and means for illuminating said light signal with a series of flashes during each period the said arm is being vibrated.
17. In a highway signaling apparatus, the combination with a support, of an arm disposed in a substantially horizontal position, an electric lamp signal on said arm, a motor, mechanism driven by said motor for imparting a succession of vibratory movements to said arm, and means for illuminating said lamp signal with a series of flashes during each period the said arm is being vibrated.
18. In a highway signaling apparatus, the combination with a support, of an arm disposed in a substantially horizontal position, an electric lamp signal on said arm, a motor, cam mechanism driven by said motor for imparting a succession of vibratory movements to said arm, and means for illuminating said lamp signal with a series of flashes during each period the said arm is being vibrated.
19. In a highway signaling apparatus, the combination with a casing, of an arm fulcrumed near its inner end on said casing and projecting laterally therefrom, a stationary lamp signal in said casing, a second lamp signal on said arm, a motor, cam mechanism driven by said motor for imparting a succession of vibratory movements to said arm, and means of illuminating said lamp signals with a series of flashes during the period the said arm is being vibrated.
20. In a highway signaling apparatus, the combination with a support, of a movable arm which projects laterally from said support, a danger flag on said arm, means for vibrating said arm, a light signal carried by the arm, and means for causing the same to be illuminated in a series of flashes during each period of the vibration of the arm.
21. In a highway signaling apparatus, the combination with a casing formed with a light opening, of a signal lamp in said casing, a danger flag fulcrumed on the casing, means for imparting a succession of vibratory movements to the flag, and mechanism for automatically lighting said signal lamp in a series of flashes during each vibration of the danger flag.
22. In a highway signaling apparatus, the combination with a casing formed with a light opening, of a signal lamp in said casing, a danger flag fulcrumed on the casing, mechanism for imparting a succession of vibratory movements to the flag, and mechanism for automatically lighting said signal lamp intermittently during each vibration of the signal flag.

23. In a highway signaling apparatus, the combination with a support of an arm which projects laterally from said support, a danger flag supported on said arm, a bell, a motor and two cams driven thereby at different speeds for vibrating said flag and ringing said bell.

24. In a highway signaling apparatus, the combination with a support of an arm which projects laterally from said support, a danger flag supported on said arm, a bell and

an electrical signal lamp, a motor and mechanism driven by said motor for imparting a series of vibrating movements to the flag, sounding the bell and making and breaking the lamp circuit a plurality of times during each cycle of operation of the flag.
